W. R. HALL.

SPARK ARRESTER.

APPLICATION FILED APR. 4, 1914.

1,127,989.

Patented Feb. 9, 1915.

UNITED STATES PATENT OFFICE.

WILLIAM R. HALL, OF WARNER, NEW HAMPSHIRE.

SPARK-ARRESTER.

1,127,989.

Specification of Letters Patent.

Patented Feb. 9, 1915.

Application filed April 4, 1914. Serial No. 829,719.

To all whom it may concern:

Be it known that I, WILLIAM R. HALL, a citizen of the United States, residing at Warner, in the county of Merrimack and 5 State of New Hampshire, have invented certain new and useful Improvements in Spark-Arresters, of which the following is a specification.

The present spark arrester invention is 10 designed as an improvement on my previous Patent No. 1,016,069 dated January 30, 1912, the object in view being to provide a more efficient device and compact arrangement embodying agitating means for dislodging the soot and sparks which are collected by the baffle member of said device.

In carrying out my invention I employ in conjunction with a baffle member an agitator of special form comprising a fan revolvably mounted in the baffle and carrying knocking elements designed to contact with the baffle to loosen foreign matter adhering thereto when the fan is operated, the latter member effectively removing away from 25 the baffle said foreign matter after dislodgment.

A further object of my device is to provide operating means for the agitator so constructed as to facilitate the assembling 30 and dismantling of the parts of the device, said operating means being arranged to interlockingly coöperate when in normal operative position to maintain the proper relative position of the operating elements.

It will be obvious to those skilled in the art that changes may be readily made in the details of construction and conformation of the device according to the use to which it is to be put without departing from the 40 spirit of the invention, and within the scope of the appended claims.

Reference will now be had to the accompanying drawings forming a part of this specification, wherein:

Figure 1 is a side elevation of a device embodying my invention partly broken away and in section to show more clearly the details of construction. Fig. 2 is an end elevation partly broken away and in section of the operating mechanism. Fig. 4 is a top plan view of the invention. Fig. 5 is a detail plan view of the journal bar for the agitator.

Throughout the following detail description, and on the several figures of the draw-

ings, similar parts are referred to by like reference characters.

Referring to the drawing and describing specifically the device illustrated thereby, the numeral 1 designates a baffle or cage 60 similar to that of my previous patent and having a band 2 at its upper open end for supporting the operating mechanism of the device. Within the baffle and substantially conforming to the shape of the same is disposed an agitator which consists essentially of a fan 3 secured upon a pivot 4 in any desired manner and having connected to its lateral edges the knocking elements 5. The pivot 4 of the fan is formed with a 65 trunnion 4' at its lower extremity which is journaled in a bearing 6 disposed in the lower conical extremity of the baffle while the upper end of the pivot 4 has its bearing in a horizontal transverse bar 7 most distinctly shown in Fig. 5 of the drawing. This bar is disposed in the lower portions of the spaced standards 8, 8' secured to the band 2 by means of rivets 9, or similar fastening members and furthermore the bar 75 is provided with an open ended and curved slot 10 in which the upper extremity of the pivot 4 for the agitator is normally disposed when this member is in proper operative position within the baffle. The upper 80 extremity of the pivot 4 is provided with a beveled pinion 11 by means of which the agitator is adapted to be rotated, in a manner more clearly described hereinafter.

The operating means for rotating the 90 agitator consists of a shaft or spindle 12 journaled in the upper portions of the standards 8, 8' which are suitably apertured to permit of insertion of said shaft by longitudinal movement thereinto. The shaft 95 12 carries a driving gear 13 which is mounted for longitudinal movement with respect to the shaft and when in an operative position is connected for rotation with the shaft by a spline or lug 14 formed on the 100 latter, said spline engaging in a recess in the hub of the gear for interlocking connection of the latter with the shaft as most clearly depicted in Fig. 1 of the drawing. The standard 8' is suitably formed with a 105 slot or aperture 15 to permit the passage of the spline 14 therethrough in assembling the parts for proper coöperation in the actual use of the device. One extremity of the shaft 12 is provided with a crank 16 for 110

imparting rotation to the shaft when the agitator is to be operated. The opposite end of the shaft 12 is provided with a locking member 17 for retaining the shaft in position on the standards 8, 8' and this locking member performs a peculiar function in that it maintains the operating parts of the device in their proper coöperative relation with respect to each other as will be 10 apparent from the foregoing description and reference to the drawing.

In assembling the device, as hereinbefore inferred, the agitator 3 is disposed within the baffle 1, its pivot 4 being properly positioned in the lower bearing 6 and the upper bearing bar 7, whereupon the shaft 12 is inserted in the standard 8', the gear 13 being then slipped upon the shaft which is finally passed through the aperture of the opposite 20 standard 8. The longitudinal movement of the shaft into this position brings the spline 14 into coöperation with the hub of the gear and by slipping said spline into the recess of said hub the gear is locked for rotation therewith. Furthermore, the complete longitudinal movement of the shaft 12 as above described forces the gear 13 into intermeshing 25 relation with the pinion 11 whereupon the locking member 17 is inserted and the 30 elements locked in proper operative position.

As shown in Fig. 1 of the drawing, the knocking elements 5 are movably connected to the lateral edges of the fan 3 and consist 35 in this instance of ring members or short pieces of chain secured in the apertures 3'. Any suitable number of these knockers may be employed and I do not wish to be confined to the particular nature of knocking elements 40 illustrated since it is entirely within the purview of the invention to employ various other members of a similar nature which will perform the function hereinafter set forth.

45 When the baffle or cage 1 becomes coated with soot and other byproducts of combustion which usually pass through the passage in which a device of this character is disposed, said foreign matter may be readily and quickly dislodged therefrom by imparting rotation to the shaft 12 which, through 50 the gearing, will cause the agitator to revolve and such revolution of the agitator will throw the knocking members 5 into contact with the baffle thereby dislodging such matter to enable the same to be forcibly blown away from the baffle by the fan 3 which carries the knocking elements. The in-

timate contact of the knocking elements of the baffle in the revolution of the agitator 60 within the same insures complete removal of adhering sparks and soot therefrom and a most efficient device is thus provided.

It will be apparent that the invention hereinafter described may be made of such 65 conformation and size as to permit of its disposition within stove pipes, chimneys, or fireboxes as may be desired and if the disposition of the arrangement is such as to require the same any suitable operating connection may be provided for the shaft 12 to enable the operator to rotate the same. This connection I have shown in the drawing to consist of a sprocket and chain 18 and 19 respectively leading to a convenient point 70 of access. I desire also not to be limited to the use of a single fan tree as it is clearly within this invention to provide a fan which is constructed within several wings and which would accomplish the same function 80 as hereinbefore described with reference to the preferred form.

Having thus described my invention, what I claim as new is:

1. In a spark arrester, the combination of 85 a baffle, agitating means coöperating therewith and comprising knocking elements adapted to impart blows to the baffle for dislodging matter from the baffle, and means for operating said knocking elements, said 90 means forcibly removing away from the baffle said dislodged matter.

2. In a spark arrester, the combination of 95 a baffle, agitating means coöperating therewith and comprising knocking elements adapted to impart against the baffle for dislodging matter from the baffle, means carrying said knocking elements adjacent to the latter when inoperative and arranged to cause the same to contact with the baffle upon 100 operation of said means, and means for operating the carrying means.

3. In a spark arrester, the combination of a baffle, agitating means coöperating therewith and comprising a rotatable member 105 journaled within the baffle, a plurality of knocking elements loosely connected to the rotatable member, and means for rotating the rotatable member to cause impact of the 110 knocking elements on the baffle.

In testimony whereof I affix my signature in presence of two witnesses.

WILLIAM R. HALL.

Witnesses:

ANDREW J. HOOK,
FANNIE A. HALL.
